Fig. 2.

Fig. 3.

Fig. 4.

Fig. 1 is a front side perspective, with the landing gear retracted, of a rotary wing aircraft, showing my new design.

Fig. 2 is a plan view of the same.

Fig. 3 is a side elevation of the same, with the landing gear down.

Fig. 4 is a front elevation of the same.

The opposite side of the aircraft is essentially like that shown in the drawings.

I claim:

The ornamental design for a rotary wing aircraft, as shown and described.
